US00D921009S

(12) **United States Design Patent** (10) Patent No.: **US D921,009 S**
Connors et al. (45) Date of Patent: **** Jun. 1, 2021**

(54) **DISPLAY SCREEN OR PORTION THEREOF WITH GRAPHICAL USER INTERFACE**

(71) Applicant: **Keurig Green Mountain, Inc.**,
 Burlington, MA (US)

(72) Inventors: **Michael Connors**, Lutz, FL (US);
William Pacheco, Raynham, MA (US);
Lisa Fortini Watts, Medford, MA (US)

(73) Assignee: **Keurig Green Mountain, Inc.**,
 Burlington, MA (US)

(**) Term: **15 Years**

(21) Appl. No.: **29/706,295**

(22) Filed: **Sep. 19, 2019**

(51) LOC (13) Cl. **14-04**

(52) U.S. Cl. **USPC .....** **D14/485**

(58) **Field of Classification Search**

USPC D14/485-495
 CPC G06F 3/048-04897

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken line rectangle represents a display screen or portion thereof. The remaining broken lines represent portions of a graphical user interface. None of the broken lines form part of the claimed design.
